W. Emmons.

Horse Power,

Patented Dec. 24, 1834.

Sellers Patent.

The Schedule is referred to in this Letter's Patent, and making part of the same containing a description in the words of the said William Commons himself of his improvement in the Horse Drawn

To all to whom these presents shall come,

I Doit. know that I William Commons of the City and County of New York have invented a new and useful improvement in the horse Draw and that the following is a full and exact description of the construction and operation of the said Horse Draw as invented by me viz. The frame is constructed by placing two sticks of timber of about thirteen feet, in length, parallel with each other and about twenty inches distant apart, ten pieces of timber about eight inches deep and five inches thick are notched in and then bolted across the above thirteen foot pieces. On and across the opposite end of said thirteen foot pieces is placed a piece of plank about four inches thick and one foot wide and supported in an edgewise position by braces. a piece of plank about three feet long is fitted in between said thirteen foot pieces on which is placed the steps to receive two upright shafts. The upper ends of said shafts being supported by journals and braces bolted to the top timber of the frame. The first or main shaft is about four inches square and extends a sufficient height above the frame to receive the main or driving cog wheel which is about thirty inches in diameter. Said cog wheel meshes into a pinion of about one fourth of its size on the second upright shaft which is about two and a half inches square. on the lower part of said second shaft between the top and bottom timbers of the frame is placed a rock wheel about twenty inches in diameter. Said rock wheel meshes into a pinion of about one fourth of its diameter on a horizontal iron shaft which is about one and a half inch in diameter, and is turned by journals and braces in a position parallel with and between the bottom pieces of the frame. on the opposite end of said horizontal shaft is placed a spur wheel of about eighteen inches in diameter which meshes into a pinion of about one third or fourth of the size of said spur wheel. Said pinion being turned to the central part of the draw which is about two feet in diameter and being on a foot or spindle of sufficient strength projecting from the end plank of the frame. four logs of about ten feet in length are

secured to the main or driving wheel. They working against projection on the rim of said wheel at right angles with each other. The outer ends being elevated about two and $\frac{1}{2}$ feet from the bottom timbers of the frame. Bars
are placed between said levers to keep them at equal distances apart.
The Horseshoe is hitched to the outer ends of said levers - and in the circle of
this wheel, steps over the bottom timbers of the frame which are planted
over the spur wheel on the horizontal shaft; also the down being inside
the circle of the Horseshoe wheel. I sometimes place the main cog wheel and
pinion below the top timbers of the frame, in which case a suitable
flange is placed on the top end of the main shaft, to which the levers
are secured. What I claim as my invention and improvement is
the proportion and peculiar arrangement of the several parts of the above.
